UNITED STATES PATENT OFFICE

2,081,027

TELEPHONE SYSTEM

John Wicks, Oak Park, Ill., assignor to Automatic Electric Company, Limited, Liverpool, England, a British company

Application May 13, 1935, Serial No. 21,199

22 Claims. (Cl. 179—18)

The present invention relates to telephone systems. It is concerned particularly with telephone systems in which the interconnection between lines is effected through the operation of automatic switching apparatus. The object of the invention is to produce a new and improved telephone system in which the amount of equipment withheld from common use by reason of a conversational connection having been set up between a pair of lines is at a minimum.

General description

In carrying out the general object of the invention, and in applying the invention to automatic telephone systems, two separate trains of switches are provided, one to be used exclusively for the setting up of connections from a calling line to a desired line, while the other train includes switches positioned under the control of the switches in the first-named train and through which the conversational connections are established. It will be understood, therefore, that the invention is applied to the improvement of what is known as separate-setting and speaking-route systems. One feature of the invention resides in the arrangement whereby the setting switches (or the by-pass switches, as they are sometimes called) are maintained entirely separate from the conversational switches with no fixed relationship as to the relative numbers, while at certain switching stages temporary interconnection between setting and conversational switches is provided by means of what are referred to as tie switches. Through the interconnection temporarily effected by means of the tie switches, the conversational switches are positioned according to the position taken up by the setting switches, the positioning of the conversational switches being, in general, accomplished by a hunting movement to hunt for a conversational switch in a group marked according to the positioning of the by-pass or setting switches.

A feature of the disclosure is that all of the conversational switches, including those used for the purely non-numerical or preselection stage, are of the same rotary type of switch mechanism, each having access to one-hundred outlets.

A further feature is that the switches in the by-pass train which respond to setting impulses are of the Strowger vertical and rotary type, while the switches in the conversational train are of the rotary or single-motion type.

A further feature resides in the arrangement for providing a common group of finder distributors for a number of 100-line groups of finders.

A further feature of the disclosure is that a by-pass final selector has access to five 100-line groups of subscribers' lines, being controlled by the preceding hundreds by-pass selector to determine to which of the five 100-line groups the connection is to be extended.

A further feature is concerned with the provision of a group-common conductor at each of a plurality of switching stages for controlling the hunting operation of the tie switches hereinbefore referred to. All of the conversational switches which have access to the same group of outlets or trunks are considered as a group. A group-common conductor is assigned to the group of switches. A multiple of this conductor appears in each of the trunks accessible to the group of switches, as well as in each of the outlets from the tie switches to a conversational switch of the group, and is useful in directing the tie switches so that connection is made thereby to a conversational switch having access to a trunk line over which the desired conversational connection may be completed, or to direct the operation of the tie switch so that it makes connection with the trunk line to which a predetermined conversational switch has access.

The invention also includes a number of additional features of novelty in a system such as briefly outlined above, as will appear more fully hereinafter.

Description of drawings

Referring now to the accompanying drawings, comprising Figs. 1 to 12, they show by means of the usual circuit diagrams a sufficient amount of the equipment in a telephone system embodying the invention to enable the invention to be understood. More in particular, Figs. 1 to 6 show switching apparatus through which a connection may be set up from the line of substation A, Fig. 1, to the line of substation B, Fig. 6; Figs. 7 to 12 show common controlling or by-pass equipment forming a train of setting or by-pass switches which are taken into use temporarily while a connection is being established, but which forms no part of the established talking connection; and Fig. 13 (on the same sheet as Fig. 3) shows an overflow circuit to which an attempted connection may be routed in the event that an all-trunks-busy condition at a given switching stage precludes the completion of the connection to the desired line.

In the conversational train, two non-numerical switching stages are provided, represented respectively by the primary finder PF, Fig. 1, and

the secondary finder SF, Fig. 2; three numerical or selecting switching stages are provided, represented by the thousands selector TS, Fig. 3, the hundreds selector or pre-final selector PS, Fig. 5, and the connector or final selector FS, Fig. 6. When the usual decimal system is followed, the three numerical switching stages afford an ultimate capacity of ten thousand lines.

Each of the single-motion rotary switches of Figs. 1 to 6 is assumed to have fifty contacts in the bank of each wiper, as is indicated by the numeral (50) located adjacent each of the above-named switches. By the expedient of providing a duplicate set of wipers, as shown, the capacity of each switch is increased to one hundred outlets.

The grouping of the conversational switches, and the arrangement of the switches in the by-pass train will now be considered.

From the standpoint of the by-pass train of switches, the originated calls are distributed by distributors such as DS, a group of which is assigned to five 100-line groups of subscriber lines in the present disclosure. Each distributor is provided with a tie-switch such as the tie switch TS1, each of which has access to fifty primary finders, such as the primary finder PF, Fig. 1. It is assumed that ten primary finders suffice to serve a one-hundred line sub-group, and that fifty finders, therefore, serve five 100-line groups, all accessible from one fifty-outlet switch, such as the tie switch TS1, Fig. 7.

As many distributors as may be required are assigned to the 500-line group above discussed, one additional distributor being indicated, the distributor DS', having the tie switch 'TS1'. The banks of the several tie switches of the same group are suitably multiplied together, as is indicated by the inter-bracket line 740.

In common with the other distributors associated with the same 500-line group, and with distributors at other 500-line groups, the distributor DS has access to twenty-five by-pass thousands selectors, of which the by-pass thousands selector PTS, Fig. 9, is one. Accordingly, each of the semi-circles of bank contacts associated with wipers of the distributor DS contains twenty-five contacts, as indicated by the numeral (25) placed above the switch. This number, of course, is somewhat arbitrary, as a larger number or smaller number may be used in practice.

In common with other by-pass thousands selectors, the by-pass thousands selector BTS, Fig. 9, (having ten levels of bank contacts) may have access to ten groups of by-pass pre-final selectors, of which the by-pass pre-final selector BPS, Fig. 11, is one.

For the purpose of testing called lines and guiding final selectors (such as the final selector FS, Fig. 6) into association with desired called lines by-pass final selectors (such as the by-pass final selector BFS, Fig. 12) are provided, each of which has access to the terminals of the lines in five 100-line groups. Accordingly, the same by-pass final selector may be reached over five levels of the by-pass pre-final selectors. The terminals shown in association with the wipers 1114-1118 of the by-pass pre-final selector BPS, Fig. 11, are assumed to be the first terminals in levels 1 to 5. It is to be noted that, as regards the terminals accessible to wipers 1115, 1116, and 1118, the terminals of the five levels indicated are multiplied together and are connected to conductors 1137, 1136, and 1130, extending to the by-pass final selector BFS. The second terminals in the same levels may be

similarly multiplied together and connected to the second by-pass final selector, and so on. With this arrangement, the same by-pass final selector may be seized responsive to a dialled digit which directs the by-pass pre-final selector to any one of five levels. In order, therefore, that the by-pass final selector shall be able to distinguish between five one-hundred line groups to which it has access, the contacts accessible to the line-test wiper 1117 of the by-pass pre-final selector BPS are not multiplied together, but each extends to a separate wiper of the by-pass final selector BFS, whereby the hundred-line group with which effective connection is made is determined by the level over which the by-pass final selector BFS is seized. The fifth to tenth levels of the by-pass pre-final selector BPS are similarly associated with another 500-line group, by way of another group of by-pass final selectors.

The function of the non-numerical stage tie switch TS1, Fig. 7, having been described generally, attention will now be directed to the first-stage and second-stage tie switches TS2 and TS3, Figs. 8 and 10. The tie switch TS2, Fig. 8 has access to a maximum of fifty finder-selector links, such as the link interconnecting the secondary finder SF, Fig. 2, with the thousands selector TS, Fig. 3. When the by-pass thousands selector BTS, Fig. 9, is seized (over conductors 741-745 by a distributor such as the distributor DS, Fig. 7), the tie switch TS2 is caused to operate to select an idle link of which the secondary finder, such as the finder SF, has access to the primary finder (such as the primary finder PF,) taken for use by the tie switch TS1. Thereafter, the circuits of Fig. 7 and Fig. 8 cooperate to cause the secondary finder to hunt for and connect with the primary finder used to find the calling line, whereby the conversational path from the calling line is set up through a primary finder and a secondary finder as far as a thousands selector, such as the thousands selector TS, Fig. 3.

When the by-pass pre-final selector BPS, Fig. 11, is seized (by way of conductors 931-935 by a by-pass thousands selector, such as the selector BPS, Fig. 9), the tie switch TS3 is caused to select a trunk line extending to a pre-final selector (such as the selector TS, Fig. 5) which is accessible to the particular thousands selector, such as TS, taken for use by the preceding tie switch, such as TS2. Thereafter, the circuits of Figs. 8 and 10 cooperate to position the thousands selector on the trunk selected by the tie switch TS3, whereby the conversational path from the calling line is extended as far as a pre-final selector, such as the selector PS, Fig. 5.

Subsequently, a level-common conductor, such as the fifth-level-common conductor 1138, is marked by the positioning of the by-pass pre-final selector BPS, and the seized pre-final selector PS is controlled from the circuits of Fig. 10 to select a final selector in the group indicated by the level to which the by-pass pre-final selector BPS has been operated.

Subsequently, the seized by-pass final selector (such as the by-pass final selector BFS, Fig. 12) is operated to make connection with the called line and to enable it to be tested to ascertain its busy or idle condition, following which the selected final selector, such as the final selector FS, Fig. 6, is caused to complete the conversational connection to the line (if idle) under the control of the circuits of Fig. 10, in cooperation with the circuits of Fig. 4, and as determined by the positioning of the by-pass pre-final selector and the

by-pass final selector (such as BPS, Fig. 11 and BFS, Fig. 12).

As will be subsequently explained in detail: (1) the connection set up to a by-pass thousands selector, such as BPS, Fig. 9, through a distributor such as is indicated in Fig. 7 is released as soon as the conversational connection has been completed to a thousands selector, such as TS, under the control of the non-numerical-stage and first-stage tie switches, whereafter the connection between the calling line and the by-pass thousands selector is maintained through a tie switch such as the tie switch TS2; (2) as soon as the connection has been further extended by a thousands selector (such as TS, Fig. 3), to a pre-final selector (such as FS, Fig. 5), the by-pass thousands selector (such as BPS, Fig. 9), and associated tie switch are released, and the connection to the by-pass pre-final selector (such as BPS) from the calling line is maintained through a tie switch, such as TS3; and (3) as soon as the connection has been completed to the desired line (through a pre-final selector such as PS, Fig. 5), and a final selector (such as FS, Fig. 6), the connection from the calling line to the by-pass pre-final selector (such as BPS, Fig. 7, by way of a tie switch such as TS3) is released, and the by-pass pre-final selector, together with the by-pass final selector, is released and restored to common use.

From the general description given above of the operation of the system, it may be seen that a first-stage tie-switch, Fig. 8, in testing the finder-selector links to which it has access, must not only find an idle link, but must find an idle link of which the secondary finder such as SF has access to the same primary link to which connection has been made by the non-numerical tie switch, Fig. 7, as it would be futile to select an idle link in a group that does not have access to the primary finders in the calling group. In order to enable this group test to be made, a group-common conductor 200 is assigned to the group of secondary finders in which the secondary finder SF is located. All of these secondary finders have their banks connected in multiple in the regular way, and the outlets of this multiple of contacts are connected in the regular way through the distributing frame to primary finders in desired hundred-line groups. The group-common conductor 200 is multiplied to contacts on the right-hand side of the distributing frame DF1, so that an individual conductor, such as 124, of each of the primary trunks accessible to the secondary finders of the group is connected to the group-common conductor 200.

At the other end thereof, the group-common conductor 200 is multiplied to various sets of contacts at the upper side of the distributing frame DF4, so that each of the points of access from a tie switch to a secondary finder such as SF includes a conductor such as 235 connected with the group-common conductor 200. In accordance with the well known practice of keeping the trunks accessible to a given switch diversified, a tie switch such as TS2 may have access to secondary finders in a number of the groups, as outlined above, and in testing over its bank the tie switch may encounter trunks of several groups, and may successively test several group-common conductors such as 200. These group-common conductors, however, are all maintained separate from each other and no tie from one group-common conductor to another exists, whereby the group test may be accurately made

in a manner which will be described in detail hereinafter.

Similarly, a separate group-common conductor (such as 300) is assigned to each group of thousands selectors (such as TS) to direct the hunting operation at the second-stage tie switches.

Each of the several distributing frames, DF1 to DF10, shown throughout the drawings, may consist merely of suitably mounted blocks of terminals, together with inter-terminal jumper rings 10 as needed. Bank terminal wires are secured to the terminal of certain of said terminal blocks, while conductors extending to the next order of switches are secured to the terminals of other of the terminal blocks, while jumpers are run 15 between the blocks as desired to effect desired interconnections of bank terminal conductors with trunk conductors.

At this point it may be mentioned that the switches are ordinarily mounted in groups of ten or twenty and that the banks of ten switches are ordinarily permanently multiplied together by what is known as a bank multiple, and one set of bank wires is extended from one switch of the ten to a terminal block. The group of ten may 20 be further multiplied with one or more other groups of ten if desired, and the entire large group thus formed is suitably connected to trunk conductors, as is well known to those skilled in the art. This brief explanation is given for the 25 purpose of making it clear that the various distributing frames indicated are those ordinarily used in automatic exchanges for the purpose of enabling the bank terminals and the trunk terminals to be suitably connected together in the desired manner, and also to make it plain that these 30 system disclosed herein.

Detailed description

The disclosure having been described generally, a detailed description of the operation of the apparatus shown will now be given. For this purpose it will be assumed first that the subscriber at substation A, Fig. 1, desires to converse 45 with the subscriber at substation B, Fig. 6.

When the receiver is removed at substation A, line relay 104 of the individual line circuit LC energizes over conductors 101 and 102 and through contacts of cut-off relay 105. Upon operating, relay 104 disconnects the test conductor 103 of the called multiple from the test conductor of the calling multiple and connects it to ground, so as to indicate a busy condition of the calling line; at its lower armature it connects the resistor 107 in parallel with the winding of cut-off relay 105 so as to indicate the line as calling, in the banks of the finders, such as PF, having access to the calling line; and at its middle armature it places ground potential, from contacts of cut-off relay 105, on start conductor 120, assigned to the 100-line group containing the calling line.

Starting a distributor and a tie switch

Start relay 701, of the group of start relays 701-705 now operates responsive to the ground potential on conductor 120. Upon operating, relay 701 places ground potential on conductor 747 at its inner armature, while at its outer armature it connects group-mark conductor 746 to group-common conductor 751, assigned to the associated 100-line group. Conductor 751 is interconnected at distributing frame DF4 with conductor 131 associated with the primary finder PF, Fig. 1, and with each of the corresponding 75

conductors (not shown) associated with the other finders in the same 100-line group.

Start relay 708 of the distributor DS energizes through contacts of line-test relay 709 responsive 5 to the ground potential on conductor 747. Moreover, the start relay in each other idle distributor associated with the 500-line group operates at the same time. Upon energizing, relay 708 at 10 its upper armature closes a driving circuit for the self-interrupting drive magnet 720 of the non-numerical tie switch TS1, while at its lower armature it closes a driving circuit through contacts of line-test relay 709 and the selector-test relay 711 for the self-interrupting drive magnet 15 730 of the distributor DS. As a result, driving magnet 720 of the tie switch TS1, operating in a buzzer-like manner, advances the wipers 721-729 step by step over the contact bank in search of an idle link in the calling 100-line group, and 20 the driving magnet 730 of the distributor DS operates to advance the wipers 731-735 in search of an idle by-pass thousands selector. The search for an idle by-pass thousands selector by the distributor DS is carried out under the control 25 of selector-test relay 711, while the search for an idle primary finder link is carried out under the joint control of group-test relay 707 and link-test relay 710.

At its inner lower armature, start relay 708 30 energizes the polarizing windings of the electro-polarized test relay 709, 710, and 711. None of these relays operates responsive to the energization of its polarizing winding, as it is so constructed as to require an energization also of its 35 test winding, shown in each case as the upper winding of the relay.

Distributor seizes an idle by-pass thousands selector

40 It will be assumed that the by-pass thousands selector BPS, Fig. 9, is the first one found to be idle by the distributor DS. That being the base, when wipers 731-735 arrive on the contacts from which conductors 741-745 extend, test wiper 733 45 encounters a negative potential on conductor 743 by way of the contacts of make-busy key 812, armature 843 of relay 804 and its resting contact, conductor 853, off-normal contacts 907 of the selector BPS, and the upper winding of 50 series relay 903. The encountering of this potential by test wiper 733 of the distributor DS results in the closure of an effective circuit through contacts of clear-out relay 712, contacts of line-test relay 907, the test winding of selector-test 55 relay 711, and the middle lower armature of start relay 708 to ground. Selector-test relay 711 immediately operates over this circuit and opens the driving circuit of magnet 730 at its lower armature, thereby stopping the wipers of 60 the distributor in engagement with the idle by-pass thousands selector BPS, it connects the transfer wiper 735 to the lower winding of transfer relay 713, it immediately marks the by-pass thousands selector BPS engaged by shunting its 65 test winding, thereby applying ground potential directly to test wiper 733; and at its upper armature it connects negative wiper 731 with positive wiper 732 through contacts of line test relay 709, thereby effecting an immediate energization of 70 line relay 901 of the by-pass thousands selector BPS with the results to be described hereinafter.

Tie switch seizes a primary finder

As the wipers 721-729 of the tie switch TS1 75 are driven over their contact banks by driving

magnet 720, group-test wiper 721 successively connects the upper terminal of group test relay 707 to conductors such as 131, but this is without effect until wiper 721 engages a contact associated with a link assigned to the calling 100-line group, the link extending to the primary finder PF, for example. When wiper 721 reaches the terminal to which conductor 131 is connected, a circuit exists for group-test relay 707 from the right-hand terminal of the secondary winding of 10 the transformer 706 (individual to the distributor DS) through test relay 707, group-test wiper 721, and conductor 131 to group-common conductor 751, and thence by way of contacts of the start relay 701 and group-test conductor 146 15 to the left-hand terminal of the secondary winding of transformer 706. Group-test relay 707, together with other similar test relays throughout the disclosure, is of the shaded-pole type of 20 alternating current relay, the shaded pole preventing chattering of the contacts in the well-known manner. Upon operating, relay 707 extends a ground potential from the inner-lower contacts of the energized start relay 708 to the test winding of link-test relay 710, and thence to 25 link-test wiper 726. Assuming that the link extending to the primary finder PF is idle, the test winding of link-test relay 710 is energized over conductor 136, through contacts of switching relay 119 of the primary finder PF, make-busy key 30 134, and resistor 118. Upon operating, link-test relay 710 immediately shunts its test winding so as to apply ground potential directly to conductor 136 and thereby mark the link engaged and it opens the driving circuit of magnet 720 35 of the tie switch TS1 so as to stop the wipers 721-729 in engagement with the terminals of the link extending to the primary finder PF.

As soon as link-busy relay 710 and selector test relay 711 are both operated, indicating that the 40 switches TS1 and DS are both positioned, a test circuit is prepared for the upper winding of line-test relay 709, and a driving circuit for the seized primary finder PF is closed through contacts of relays 709, 710, and 711 by way of drive wiper 45 722. Since the primary finder PF is the one that has been selected, wiper 722 is standing on the terminal of conductor 132, and the circuit extends to self-interrupting driving magnet 117 of the finder PF. Accordingly, magnet 117 starts to 50 drive the wipers 111-116 in search of the calling line. At the same time, ground potential is applied to the right-hand terminal of the test winding of line-test relay 709 through contacts of 55 relays 710 and 711, enabling line-test relay 709 to test the lines as to their calling or non-calling condition, through line-test wiper 723, test conductor 133, and test wipers 113 and 116 of the finder PF.

Primary finder seizes the calling line

When the wipers of the primary finder PF arrive on the terminals of the calling line, test wiper 113 completes a test circuit for line-test relay 709, Fig. 7, through contacts of cut-off relay 65 105, contacts of the energized line relay 104, and resistor 107. It is to be noted that the line-test relay 709 will not operate through a cut-off relay which is not shunted by a resistor such as 107.

Upon operating, line-test relay 709 opens the 70 driving circuit of the primary finder PF, and shunts its test winding at its inner upper armature so as to mark the calling line engaged in the finder (or calling) multiple. Cut-off relay 105 removes ground potential from start conductor 75

120; disconnects resistor 107 and substitutes meter 106, and it disconnects ground potential and the line relay 104 from conductors 102 and 101.

5 In the distributor, line-test relay 709 also connects the positive and negative wipers 724 and 725, through the corresponding wipers 732 and 731 of the distributor, to conductors 742 and 741 of the by-pass thousands selector BPS, at the 10 same time removing the preliminary energizing bridge previously closed through the upper contacts of selector test relay 711. The line relay 901 of the by-pass thousands selector BPS is henceforth held energized over the calling line 15 through wipers 112 and 111 of the primary finder PF.

Line-test relay 709 of the distributor also opens a point in a special locking circuit for the upper winding of transfer relay 713 at its lower armature, and at its inner lower armature it disconnects start relay 708 from the associated conductor 741 and extends it through contacts of clear-out relay 712 to test wiper 733, at the same time disconnecting wiper 733 from the ground 25 potential previously applied to the test wiper through contacts of selector test relay 711 and the middle lower armature of start relay 708. The continued energization of start relay 708 is therefore dependent on ground potential applied 30 to test conductor 743 by way of make-busy key 812, contacts of relays 804 and 808, conductor 853, and contacts of the now-energized release relay of the selector BPS. It is to be noted that the winding of start relay 708 is shunted by a 35 resistor. This shunt circuit around the winding of relay 708 has a slight tendency to make the relay slow releasing, so as to prevent a restoration of the relay while its circuit is being transferred from conductor 741 to test wiper 733.

40 Start relay 701, assigned to the 100-line group containing the line of substation A, now deenergizes responsive to the above-mentioned operation of cut-off relay 105, unless there is another calling line in the same 100-line group. At this 45 time, conductor 741, common to five start relays 701-705, becomes ungrounded unless there is an unfound calling line in one of the five 100-line groups associated with distributor DS. Keeping in mind, that each idle distributor in the 50 group containing the distributor DS is started into operation responsive to the starting ground potential on conductor 741, it will be appreciated that all other distributors may stop operating and clear out responsive to the removal of ground 55 potential from conductor 741 when relay 701 restores.

Result of seizure of by-pass thousands selector BPS

60 When the by-pass thousands selector BPS is seized as pointed out, and line relay 901 has energized over conductors 851 and 852, release relay 902 is operated by the line relay through contacts of the electro-polarized switching relay 904. At 65 its lower armature, release relay 902 opens a point in the circuit of release magnet 912 and prepares a circuit for vertical magnet 910; at its inner upper armature it applies ground potential to the polarizing winding of switching relay 804; it applies ground potential to start conductor 855 to 70 start the associated tie switch TS2 into operation; it places ground potential on conductor 853 so as to provide a holding circuit for the seizing distributor DS; and it connects the test winding of 75 switching relay 904 to the test wiper 923.

As a result of the ground potential on conductor 853, the upper winding of series relay 903 is energized through off normal contacts 907. Relay 903 thereupon operates and disconnects rotary magnet 911 at its inner lower armature; 10 closes a further point in the vertical-magnet circuit at its lower armature; and at its upper armature it disconnects ground potential from the lower winding of line relay 901 and substitutes ground potential through over-flow contacts 909 and the secondary winding of dial-tone transformer 951. Accordingly, the calling subscriber is given a dial-tone signal to indicate that he may now begin to dial the digits of the desired number. 15

Starting the first-stage tie switch

When ground potential is applied to start conductor 855 by release relay 902, a circuit is closed for pulse relay 801 through armature 844 and the 20 inner upper armature of link-test relay 803. Pulse relay 801 thereupon operates in series with drive magnet 820, and closes a direct circuit for the magnet, thereupon magnet 820 operates and opens the circuit of pulse relay 801. Relay 801 25 thereupon restores and opens the circuit of driving magnet 820, permitting drive magnet 820 to restore and again close a circuit for the pulse relay. This interaction between the pulse relay and the drive magnet continues until link-test 30 relay 803 operates through contacts of group test relay 807 and link test wiper 826, upon the encountering of an idle link associated with a secondary finder having access to the primary finder used to complete the connection to the 35 calling line.

As the wipers 821-830 are rotated over the contacts by the above action of drive magnet 820, group test wiper 825 connects group-test relay 807 successively to group-test conductors such 40 as 235, but this is without result until the tie switch TS1 has become positioned as pointed out, and relay 710 has operated. After relay 710 operates, each time wiper 825 encounters a link in the group (containing the finder SD) 45 predetermined by the selection of the primary finder PF, a circuit is closed over a conductor such as 235 for the group-test relay 807 and group test relay 807 thereupon responds to connect link-test relay 803 to link-test wiper 326. The source 50 of current for operating group-test relay 805 is the secondary winding of the transformer 811 (individual to the circuit illustrated), to which the relay is connected through the inner lower armatures of switching relay 805 and stop relay 55 804. The other terminal of the secondary winding of the individual transformer 811 is now connected through the middle lower armature and resting contact of switching relay 805, conductor 744, marking wiper 734 of the distributor DS, 60 contacts of the energized test relays 710 and 711, contacts of transfer relay 713, group-mark wiper 729, and conductor 124, to the group-common conductor 200, assigned to the secondary finder group including the secondary finder SF. This 65 secondary finder group has been definitely marked by the position of the group-mark wiper 729 of the tie switch TS1, as conductors 139 and 124 lead only to the group-common conductor 200. It will be understood, of course, that other 70 primary finders may have their conductors such as 144 interconnected with other secondary finder groups and therefore with other group-common conductors instead of to conductor 200.

With group-test relay 807 operated over group- 75

common conductor 200 as above explained, the link-test relay 803 is connected to link test wiper 826 and is thereby permitted to test the links passed over which belong to the secondary finder group to which the group-common conductor 200 is assigned.

Seizing an idle secondary finder, SF

It will be assumed for convenience that the link including the secondary finder SF is the first link of the pre-selected group found to be idle, in which case the rotation of the wipers of the tie switch TS2 continues until the terminals of this link are reached, whereupon link-test wiper 826 encounters conductor 236 on which a battery potential is placed by way of resistor 210, make-busy contacts 209, and contacts of switching relay 208. Link-test relay 802 now energizes and terminates the hunting operation of the switch. Relay 803 also prepares a circuit for stop relay 804, but this circuit does not become immediately effective, as it is maintained open at the inner lower armature of clear-out relay 808, which relay is maintained operated at the lower contacts of pulse relay 801 throughout the hunting operation.

A moment after the hunting operation has been terminated by the energization of link-test relay 803, the slow releasing relay 808 restores and completes the energizing circuit of stop relay 804. Relay 804 thereupon closes a locking circuit for itself at its preliminary-make contacts 845; it opens a further point in the hunting circuit at armature 844, as well as its own initial circuit; at armature 843 it breaks one point in the interconnection between conductors 853 and 854, leaving these conductors connected together through the inner upper contacts of the now-restored clear-out relay 808; at armature 842 it applies direct ground potential, by way of wiper 826, to conductor 236 so as to guard the link against further seizure; and at armature 842 it prepares a drive and link-test circuit under the control of drive relay 802. At its inner lower armature, stop relay 804 disconnects group-test relay 807 and substitutes line test relay 806, while at its lower armature it connects up drive relay 802 for a purpose to be explained more fully hereinafter.

Preventing false seizure

At this point, it may be pointed out that the above-mentioned clear-out relay 808 is energized during the hunting operation of the tie switch TS2 to maintain the circuit of stop relay 804 opened momentarily after link-test relay 803 has operated so as to prevent a possible false operation which otherwise might occur as follows: assuming that the test for an idle link starts with the wipers of the tie switch standing on one of the last few links of the group and that they are all busy, group-test relay 807 operates but link test relay 803 cannot operate over any of the test conductors of the busy links in the group, but in the event that the first link of the next following group is idle there is a possibility that link test relay 803 may operate before group test relay 807 has had time to restore. With the circuit of relay 804 maintained opened for a slight interval by clear-out relay 808, a spurious operation of relay 803 such as above pointed out results merely in a momentary cessation of the driving movement, as this movement is resumed as soon as group-test relay 807 restores and opens the circuit of link-test relay 803 and permits it to restore. This operation occurs before the slow-

releasing clear-out relay 808 has had time to fall back responsive to the temporary cessation of the operation of pulse relay 801.

Operating the secondary finder SF

When drive relay 802 is connected up at the lower contacts of stop relay 804 as above pointed out, drive relay 802 energizes over conductor 745, transfer wiper 731, and contacts of relays 711 and 712, in series with the lower winding of transfer relay 713 of the distributor DS. Transfer relay 713 disconnects mark-wiper 734 from group-mark wiper 729 and transfers it to line-mark wiper 728, preparatory to positioning the seized secondary finder SF on the particular primary finder (PF) through which connection was extended to the calling line.

Preparatory to clearing out the distributor, transfer relay 713 connects its lower winding directly to transfer wiper 735 at its inner lower armature; closes a new holding circuit for the start relay 708 at its middle upper armature, while at its inner upper armature it closes a circuit for the slow-releasing clear-out relay 712. Relay 712 thereupon operates and prepares to release start relay 704 when transfer relay 713 restores. Transfer relay 713 also closes a point in a special locking circuit for itself at its lower armature, so as to prevent a restoration of the transfer relay and the clearing out of the circuit prior to the operation of the line-test relay 709 responsive to the primary finder PF finding the calling line.

In the tie-switch TS2, when drive relay 802 operates in series with transfer relay 713, it closes a circuit which includes the actuated armature 841, armature 848, contacts of line-test relay 806, drive wiper 821, and conductor 231, for drive magnet 207 of the secondary finder SF. The self-interrupting drive magnet 207 now operates to drive the wipers 201-206 of the secondary finder until line-test relay 806 is energized through line-test wiper 822, conductor 232, and test wiper 203 or test wiper 206, upon the primary finder in use being located.

Seizing the primary finder PF

In the assumed example, the primary finder in use is the primary PF, accessible to the wipers 201-203 of the secondary finder SF. When the wipers 201-203 arrive on the terminals to which conductors 121-123 are connected, line test relay 806 energizes through test wiper 203 and over conductor 123, the circuit including contacts of switching relay 119 of the primary finder PF, conductor 138, line-mark wiper 728, contacts of transfer relay 713, contacts of relays 711 and 710, mark-wiper 734, conductor 744, contacts of switching relay 805, secondary winding of the individual transformer 811, contacts of switching relay 805, and the inner lower armature of the operated stop relay 804.

Upon operating, line-test relay 806 opens the above-mentioned driving circuit of magnet 207 of the secondary finder SF at its upper contact, thereby terminating the hunting operation of the secondary finder, while at its inner upper armature it closes a circuit for switching relay 805. When relay 805 operates, it locks itself at armature 849 to start conductor 855; it opens an additional point in the secondary-finder driving circuit at armature 848; it connects the negative and positive conductors of the secondary finder to the corresponding conductors of the by-pass thousands selector at armatures 846 and 847; at its inner lower and middle lower armatures it

transfers the secondary winding of the individual testing transformer 811 into association with the first numerical stage; and at its lower armature it opens the circuit of drive relay 802 and transfer relay 715. Relay 802 thereupon restores and opens a further point in the driving circuit, at the same time applying ground potential from armature 841 to line test wiper 822, thereby grounding the test wipers 203 and 206 through lead 232. The ground potential on test wiper 203 is extended to conductor 123 to serve as a holding potential as soon as switching relay 119 becomes operated.

15 *Switching-through the primary finder and clearing-out the distributor*

In the distributor DS, the opening of the circuit of the lower winding of transfer relay 713 at the lower contacts of relay 805, Fig. 8, results 20 in the immediate deenergization of transfer relay 713, unless the operation of tie switch TS2 and of the secondary finder SF have taken place before the primary finder PF has found the calling line. In either event when transfer relay 25 713 does restore it opens the circuit of slow-acting relay 712 and closes a circuit through contacts of relay 712, and conductor 137, for switching relay 119 of the primary finder PF. When relay 119 operates it locks itself to the test lead, 30 now grounded by way of conductor 133 at its inner upper armature; and at its three remaining armatures it joins the wipers of the finder to trunk conductors 121, 122, and 123, at the same time disconnecting the line marking conductor 35 138 from conductor 123.

Transfer relay 713 also opens the circuit of start relay 708 for the length of time required for clear-out relay 712 to restore after its circuit is opened by the transfer 713. Relay 708 40 therefore restores and opens the circuit of the polarizing and holding windings of relays 709, 710, and 711, whereupon these three relays restore also. Line-test relay 709 disconnects the positive and negative wipers 724 and 725, therefore by opening the connection initially established between the calling line and the by-pass thousands selector PBS; line-test relay 709 also again connects start relay 708 to conductor 147 to enable the distributor DS to be again started into 50 operation pursuant to the handling of a further call. Clear-out relay 712 falls back a moment after start relay 708 restores.

The calling line is now connected with the bypass thousands selector PBS through the wipers 55 111, 112 of the primary finder PF, contacts of switching relay 119, wipers 201 and 202 of the secondary finder SF, wipers 824 and 823 of the tie switch TS2, and armatures 846 and 847 of switching relay 805. Switching relay 119 is now 60 held energized over conductor 123 through wipers 203 and 822 by the ground potential placed on wiper 822 through contacts of the restored drive relay 802, and armature 842 of stop relay 804.

From the foregoing description, it will be seen 65 that the distributor DS and the tie switch TS2 cooperate to connect the calling line very quickly with an idle by-pass thousands selector through a primary finder and that a secondary finder is subsequently operated to take over the connection 70 formed through the tie switch TS2 and the distributor DS. This arrangement serves the two-fold purpose of giving the calling subscriber quick access to a by-pass thousands selector so that he may begin sooner to dial the number, and 75 of greatly simplifying the primary and second-

ary finders at the expense of a somewhat more complicated construction at the distributor and at the tie switch TS2, which, however, are provided in much smaller numbers than the primary and secondary finders.

Dialling the thousands digit 1

When the calling subscriber, upon hearing the dial tone produced by a dial-tone current transmitted back to his line from the dial tone transformer 951, as above pointed out, dials the first digit in the desired number, line relay 901 of the by-pass selector PBS is momentarily deenergized a number of times depending upon the value of the digit. Each time it deenergizes, line relay 901 completes a circuit through the lower armatures of the operated release and series relays 902 and 903 for vertical magnet 910. By the operation of magnet 910, the wipers 921-925 are raised step by step until they come to rest opposite the desired level of bank contacts.

The lower winding of series relay 903 is energized in series with vertical magnet 910. Being provided with a conducting sleeve, as indicated, relay 903 is slow-releasing and therefore 25 remains operated throughout the series of impulses.

When the wipers of the switch leave their normal position, off normal contacts 905 prepare a circuit for release magnet 912; off normal contacts 906 prepare a circuit for rotary magnet 911; and off normal contacts 907 open the initial circuit of series relay 903, leaving the continued operated condition of relay 903 under the control 30 of the lower winding of the relay and the conductive sleeve thereof.

At the end of the digit, relay 903 restores, as no further impulses are received. Upon restoring, relay 903 removes the dial tone connection from the lower winding of the line relay 901 at its 40 upper armature and substitutes the initial direct ground potential; at its lower armature it disconnects vertical magnet 910; and at its inner lower armature it connects up the self-interrupting rotary magnet 911. Magnet 911 now operates 45 through off-normal contacts 906 to drive the wipers 921-925 until the rotary-magnet circuit is opened at the inner lower armature of the electro-polarized switching relay 904.

Seizing the by-pass pre-final selector PBS

In the assumed example, the line desired is the line of substation B, Fig. 6, the number of which is assumed to be 1513. Therefore, the first digit dialled being the digit 1, and the wipers of 55 the selector PBS are brought to rest opposite the first level of bank contacts. The contacts shown are assumed to be the first set of contacts of the first level, being the ones from which conductors 931-935 extend to the by-pass pre-final selector PBS, Fig. 11. Assuming that the selector PBS is idle when the wipers 921-925 are rotated onto the first set of bank contacts in the first level, the test wiper 923 encounters a battery potential over conductor 933, through 60 contacts of make-busy key 1119, off normal contacts 1108, and the upper winding of series relay 1104. Test wiper 923 being connected through the upper contacts of release relay 902 to one terminal of the test winding of switching relay 70 904, the test winding is energized over conductor 854, contacts of clear-out relay 808, conductor 853, and contacts of release relay 902 to ground. Upon operating, switching relay 904 opens the driving circuit of rotary magnet 911 and the 75

circuit of release relay 902 at its inner lower armature; it makes an additional ground connection to start conductor 855; at its inner upper armature it closes the locking circuit for its polarizing and holding winding to conductor 854; it applies ground directly from the grounded conductor 853 to test wiper 923 so as to mark the seized selector BPS engaged; and it connects up wipers 921, 922, and 925, at the same time disconnecting line relay 901.

Line relay 901 thereupon restores, and release relay 902 restores a short time later, but without any particular effect at this time, as prior to the restoration of the slow releasing relay 902 ground potential has been returned over conductor 933 from the selector BPS in a manner to be pointed out later. This ground potential is extended through contacts of relay 904 to conductor 853, providing a holding circuit through contacts of clear-out relay 803 and over conductor 854 for the lower winding of relay 904, now locked to conductor 854 at the inner upper contacts of the relay.

In the by-pass pre-final selector BPS, Fig. 11, when line relay 1102 energizes over the calling line and over conductors 931 and 932, it closes a circuit for release relay 1103. Release relay 1103 thereupon operates and places ground potential at its middle upper armature, through contacts of make-busy key 1119, on conductor 933 to provide the above-discussed holding circuit for the by-pass thousands selector BPS. At its upper armature, release relay 1103 connects up test wiper 116; it energizes the polarizing winding of switching relay 1105 at its inner upper armature; at its lower armature it prepares an impulsive circuit for vertical magnet 1111; and at its inner lower armature it places a ground potential on start conductor 1119.

The by-pass pre-final selector is thereby prepared for operation in response to the second digit in the desired number and the start conductor 1119 is now grounded to start the second stage tie switch TS3 into operation.

At this point it may be well to call attention to the fact that the by-pass pre-final selector BPS is one of a number of similar by-pass selectors provided in extending calls to lines in the first 1000-line group and that the tie switch TS3, individual to the by-pass selector BPS, is started into operation to take a conversational pre-final selector, such as the selector PS, in the first 1000-line group for use pursuant to the positioning of the previously seized thousands selector TS.

Starting the second-stage tie switch TS3

When start conductor 1119 is grounded, by relay 1103, a circuit is extended through contacts of switching relay 1007, and through contacts of link test relay 1002, to the pulse relay 1001 associated with the drive magnet 1020 of the tie switch TS3. Pulse relay 1001 and drive magnet 1020 interact as described in connection with the corresponding relay and magnet, 801 and 820, Fig. 8, and magnet 1020 drives the wipers 1021-1030 in search of an idle selector in the associated #1 thousands group.

In testing for a pre-final selector, the tie switch TS3 tests for a selector which can be reached from the group including the thousands selector TS. All of the selectors in this group have access to the same trunks, and these trunks, of course, are divided more or less equally amongst the various 1000-line groups. The group-common conductor 300 is assigned to the group of thousands selectors

in which the thousands selector TS is included, and this group-common conductor is therefore connected at the distributing frame DF5 to each of the conductors such as 239 associated with a link through which a tie switch such as TS2 obtains access to a thousands selector of the group. Similarly, group-common conductor 300 is connected at the distributing frame DF2 to a conductor such as 334 of each of the conversational trunks accessible to the group of thousands selectors. It will be understood that group-common conductor 300 is one of several group-common conductors at the first stage, for there is a separate group-common conductor for each group of thousands conversational switches.

The group-common conductor 200 has been marked at the tie switch TS2 by group-mark wiper 829 by way of conductor 239. The tie switch TS3, by means of the group-test relay 1005 tests for the group-common conductor 200 marked by the tie switch TS2.

Seizing and marking the pre-final selector PS

When a trunk line accessible to the marked group of switches is reached, group-test relay 1005 operates and at its upper contacts connects the link-test relay 1002 to the link-test wiper 1005 to enable the individual links to be tested as to their busy or idle condition.

Assuming that the trunk line comprising conductors 431-440, assigned to the pre-final selector PS, Fig. 5, is the first idle one of the links accessible to the marked group, this trunk line is taken for use and the wipers 1021-1030 are stopped on the conductors 431-440. This operation includes an energization of relay 1005 over the marked group-common conductor and the subsequent operation of link-test relay 1002.

Group-test relay 1005 is connected at this time to the group-common conductor 300 by way of conductor 334 of the trunk comprising conductor 331-334, a jumper on the distributing frame DF6, conductor 431, and wiper 1021. The other terminal of group-test relay 1005 is connected through conductor 934, group-test and line-mark wiper 924 of selector BTS, contacts of switching relay 904, conductor 856, and contacts of switching relay 805, to the left-hand terminal of the secondary winding of individual transformer 811. The other terminal of this secondary winding is now connected through contacts of the operated switching relay 805, contacts of transfer relay 810, group-mark wiper 829, and conductor 349 to the group-common conductor 300. Over these circuit connections, group-test relay 1005 operates to connect link-test relay 1002 through link-test wiper 1025, conductor 435, contacts of make-busy key 411, contacts of transfer relay 408, and resistor 412, to the ungrounded pole of the exchange battery.

Upon operating over this path, link-test relay 1002 opens the driving circuit and prepares a circuit from start conductor 1119 through contacts of slow-acting series relay 1003 for switching relay 1007.

A moment later, slow-releasing series relay 1003, which is held operated throughout a series of operations of pulse relay 1001, restores and completes the circuit of switching relay 1007, whereupon relay 1007 closes a locking circuit for itself at its preliminary-make inner upper armature to the grounded start conductor 1119; it places ground potential directly on link test wiper 1025 to protect the link from further seiz-

ure by another tie switch; and it connects up the negative and positive wipers 1024 and 1023.

At its lower armature, switching relay 1107 connects transfer relay 1006 in series with transfer relay 810, by way of conductor 935, wiper 925, and conductor 857, whereupon these two transfer relays operate in series. Transfer relay 1006 switches the test-and-mark conductor 934 from the group-test wiper (by way of group-test relay 1005) into association with line-mark wiper 1022 through the inner lower contacts of switching relay 1007, thereby extending a marking potential from the secondary winding of transformer 811 to conductor 432 and thence to test conductor 333 of the trunk line incoming to the pre-final selector PS, Fig. 5, from the thousands selector TS, Fig. 3. The pre-final selector PS is thereby marked distinctively so that it will be the one seized by the thousands selector TS when the thousands selector is operated.

Thousands selector TS finds the marked pre-final selector PS

At the tie switch TS, Fig. 8, when transfer relay 810 operates, it disconnects the associated terminal of the secondary winding of transformer 811 from the group-mark wiper 825 and connects it to the line-test wiper 820 by way of line-test relay 809. In addition, transfer relay 810 at its inner armature connects drive wiper 830 to ground by way of contacts of clear-out relay 808, and at line-test relay 809, thereby closing a circuit by way of conductor 240 for the drive magnet 307 of the thousands selector TS. The drive magnet 307 is accordingly operated in a buzzer-like manner to advance the wipers 301-306 over the contact bank in search of the marked trunk-line extending to the pre-final selector PS. When this trunk line is reached, the marking potential on conductor 333 is encountered by test wiper 303, closing a circuit over conductor 223, contacts of switching relay 208, conductor 238, and line test wiper 828, for the line-test relay 809. The line-test relay 809 is thereupon energized from current supplied by the secondary winding of the transformer 811. Upon energizing, the line-test relay 809 opens the driving circuit of magnet 307 of the thousands selector TS and closes an operating circuit for the upper winding of the clear-out relay 808.

Switching through at the finder-selector link and clearing out the first-stage tie switch

At its upper armature, clear-out relay 808 places ground potential on switching wiper 827, through armature 840 of stop relay 804, thereby closing a circuit over conductor 237 for switching relay 208 associated with the link composed of secondary finder SF and thousands selector TS.

With switching relay 208 operated, and with the thousands selector TS having been positioned on the conductors leading to the pre-final selector PS, the calling line is further extended through contacts of switching relay 208, conductors 221 and 222, wipers 301 and 302, to the leading-in conductors 331 and 332, Fig. 4. From thence, the calling line is extended through contacts of release relay 403, conductors 434 and 433, wipers 1024 and 1023, and contacts of the operated switching relay 1007 to the second-stage tie switch, to line relay 1102 of the by-pass pre-final selector BPS. With this extension of the conversational path the connection previously set up through the tie switch TS2 and the by-pass thousands selector

BPS is no longer needed, and may now be cleared out.

As a further result of its above-noted operation, clear-out relay 808 opens a further point in the drive circuit, at its middle lower armature; opens the transfer lead at its lower armature, to deenergize transfer relays 1006 and 808; and at its inner lower armature it locks itself in parallel with the winding of stop relay 804 and through contacts of relay 804 to start conductor 855, now grounded at the contacts of switching relay 804. In addition, relay 808 separates conductors 853 and 854, thereby bringing about the restoration of switching relay 904, which has previously been maintained energized over the grounded conductor 933, wiper 923, conductor 853, contacts of clear-out relay 808, conductor 854, and the inner-upper contacts of relay 904. Upon restoring, relay 904 disconnects the associated wipers and also removes ground potential finally from start conductor 855.

With start conductor 855 ungrounded, stop relay 804 restores immediately, and clear-out relay 808 restores a short interval later. In addition, switching relay 805 restores responsive to the removal of ground potential from conductor 855, whereupon the relays associated with the tie switch TS2 are all in normal condition.

When switching relay 904 restores, it closes a circuit at its inner lower armature, through contacts of the restored relays 901 and 902, and through off-normal contacts 905, for release magnet 912. Release magnet 912 operates to release the selector. The release-magnet circuit is opened at off normal contacts 905 when the selector reaches normal position. In addition, off-normal contacts 907 connect test conductor 853 through the upper winding of series relay 903 to the ungrounded pole of the exchange battery so as to render the selector BPS accessible again to the distributors.

Dialling the hundreds digit 5

When the calling subscriber dials the hundreds digit 5, line relay 1102 of the by-pass selector BPS momentarily deenergizes five times. Each time it deenergizes, the line relay 1102 closes a circuit through the lower armature of the operated release relay for vertical magnet 1111, by way of contacts of idle-test relay 1012 and contacts of switching relay 1105. Vertical magnet 1111 is thereby momentarily energized five times to elevate the wipers 1114-1118 five steps, so that they come to rest opposite the fifth level of bank contacts. Series relay 1104 also receives impulses from line relay 1102 through contacts of release relay 1103, so that it remains energized throughout the series of impulses, and does not immediately restore responsive to the opening of the circuit of its upper winding at off-normal contacts 1108, when the switch leaves its normal position.

At the end of the vertical movement, series relay 1104 restores and closes a circuit through off-normal contacts 1107, and through contacts of relay 1105, for the self-interrupting rotary magnet 1112. Magnet 1112 is therefore operated to drive the wipers 1114-1118 over the bank contacts in the selected level until the rotary-magnet circuit is opened by the energization of the electro-polarized switching relay 1105 over test wiper 1116.

Seizing the by-pass final selector BPS

It may be conveniently assumed that the by-

pass final selector BFS is the first one found idle and that it is therefore seized. The seizure is brought about by the test wiper 1116 encountering a battery potential over conductor 1136 by way of off-normal contacts 1203 and the associated resistor. The test winding of switching relay 1105 is grounded at the middle upper armature of release relay 1103, and the other terminal of it is connected through the upper contacts of relay 1103 to test wiper 1116. Upon energizing, relay 1105 disconnects the rotary magnet 1112 at its middle lower armature so as to terminate the movement of the wipers; it places ground potential directly on test wiper 1116 at its inner upper armature through the middle upper armature of release relay 1103; and at its lower armature it disconnects the impulse conductor from vertical magnet 1111 and extends it through contacts of busy-test relay 1101 to the drive wiper 1118, now connected over conductor 1130 to the impulse circuit of the selector BFS.

In the seized by-pass final selector BFS, release relay 1201 energizes over test conductor 1136 and opens a point in the circuit of release magnet 1208.

Pre-final selector PS searches for an idle final selector in the marked 100-line group

As soon as the by-pass selector BPS has been positioned, the hundred-line group to which the call is directed is determined, and the pre-final selector PF, Fig. 5, may be caused to select an idle trunk line the one of the ten hundred-line groups indicated according to the level to which the by-pass selector BPS has been directed. There are ten level-common conductors such as 1138, each one associated with a different level of the by-pass pre-final selectors. Conductor 1138 is the common conductor associated with the fifth level of bank contacts, and it is connected at the distributing frame DFS to a conductor such as 522 of each of the trunks extending to the corresponding group of final-selectors. The fifth-level common conductor 1138 is now marked by group-mark wiper 1114 of the by-pass selector BPS, connected at the middle upper armature of switching relay 1105 to the lower terminal of the secondary winding of the individual transformer 1013 of the tie switch TS3. The other terminal of this secondary winding of transformer 1013 is connected through the group-and-final test relay 1011 to the group-and-final test wiper 1027, now standing on conductor 437, which is extended through contacts of relays 407 and 408 to group-test wipers 502 and 507 of the pre-final conversational selector PS.

Now, with the switching relay 1007 at the tie switch in operated condition, and with switching relay 1105 of the by-pass pre-final selector PS in operated condition, ground potential from the grounded start conductor 1118 is extended through contacts of the operated relay 1007 to the drive wiper 1030, by way of contacts of relays 1008 and 1009, and the upper contacts of switching relay 1105. Drive wiper 1030 is now standing on the conductor 440, with the result that the driving ground potential is further extended, through contacts of transfer relay 408, to the self-interrupting drive magnet 511 of the selector PS. The wipers 501-510 are accordingly driven over the contact bank in search of an idle trunk in the group marked by the marking connection made to conductor 1138 by group-mark wiper 1114, as above noted.

As the wipers are rotated, each time level-test

wiper 502, or level-test wiper 507, encounters a trunk line in the fifth group, the group-test relay 1011 is operated by current through the secondary winding of transformer 1013 and over the marked fifth-level common conductor 1138. Upon operating, group test relay 1011 applies ground potential through contacts of the stop relay 1009 to one terminal of trunk test relay 1008, the other terminal of which is connected through contacts of relay 1012 to the trunk-test wiper 1028 of the tie switch TS3. The connection is further extended over conductor 439 and through contacts of relay 408 to the trunk-test wipers 505 and 510. Therefore, as soon as an idle trunk is reached in the marked group, trunk test relay 1008 energizes through one or the other of the trunk test wipers of the switch TS to terminate the hunting movement of the selector.

Pre-final selector PS seizes the idle final selector FS

It may be conveniently assumed that the trunk extending to the final selector FS is the first one found to be idle, in which case trunk-test relay 1008 energizes through trunk-test wiper 505, and over conductor 525, from the idle-indicating potential supplied through make-busy key 611 and resistor 612. Upon operating, relay 1008 opens the driving circuit and closes a circuit for stop relay 1009. Stop relay 1009 opens a further point in the driving circuit at its middle upper armature; connects up the lower winding of the idle test relay 1012 at its upper armature; opens the circuit of delay relay 1010 and closes a locking circuit for itself to conductor 1119 at its inner upper armature; at its lower armature it places a guarding potential, through trunk-test wiper 1029 of the tie switch TS3, and through trunk-test wiper 505 of the switch PS, on conductor 525; and at its inner lower armature stop relay 1009 disconnects trunk-test relay 1008 and prepares a cut-in circuit for the relay equipment of Fig. 4.

A moment later, delay relay 1010 falls back and closes an additional point in the above-mentioned cut-in circuit.

Dialling the tens and units digits 1 and 3; reaching the called line

Following the dialling of the thousands and hundreds digits 1 and 5, the calling subscriber dials the tens and units digits 1 and 3.

When the tens digit 1 is dialled, line relay 1102 deenergizes once momentarily. When it does so, it closes a circuit through the contacts of the operated release relay 1103 for reoperating series relay 1104 momentarily. At the same time, a branch of this circuit is closed through contacts of relays 1012, 1105, and 1101, and over drive wiper 1118, for vertical magnet 1206 of switch BFS. The initial circuit for vertical magnet 1206 includes conductor 1130, a portion of the off-normal combination 1205, and series relay 1202. Relay 1202 is energized in series with vertical magnet 1206 to maintain the vertical magnet connected to the impulsing conductor and to maintain the rotary magnet disconnected after the off-normal contacts 1205 have shifted, as they do upon the beginning of the vertical movement of the switch.

At the end of the digit, series relay 1104 in the selector BPS restores. Also, series relay 1202 in the selector BFS restores, transferring the impulsing conductor from vertical magnet 1206 to rotary magnet 1207.

When the final digit 3 is dialled, three impulses are transmitted to rotary magnet 1207, and the wipers 1221-1226, having been elevated one step, are rotated over the contacts of the first level 5 until they come to rest on contact set No. 13. Of the wipers 1220 to 1225, of the selector BFS, wiper 1220 is the final-mark wiper. It marks, in the assumed example, line No. 13 in each of the five hundred-line groups to which the selector BFS has access, while wipers 1221 to 1225 10 each make connection with the test conductor (such as 623) of line No. 13 in the corresponding one of the five hundred-line groups accessible to the selector BFS.

15 *Testing the called line*

As pointed out above, series relay 1104 of the selector BFS is energized during the transmission of each of the three final series of impulses. 20 During the transmission of the series of impulses to rotary magnet 1207, constituting the final digit in the number, line-test wiper 1117 is in connection with line-test wiper 1225 by way of conductor 1135, and wiper 1225 is passing over contacts 25 connected to the test conductors, such as 623, of subscriber lines. Each time wiper 1225 passes over the test contact of a busy line, the ground potential on the test conductor of such busy line results in the operation of busy relay 1101. But 30 relay 1101 is not operated when wiper 1220 is in engagement with the test terminal of an idle line, as the test conductor of such idle line does not have ground potential thereon. With this in mind, it will be seen that busy relay 1101 is not 35 energized at the end of the rotary movement of the selector BFS if the line of substation B, Fig. 6, is idle.

Called line tests idle

40 It is assumed that the called line is idle. Busy-test relay 1101 is therefore in a deenergized condition when series relay 1104 restores at the end of the delivery of the final series of impulses, with the wipers 1220 to 1225 positioned on contact 45 set 13. Therefore, when series relay 1104 restores it closes a circuit for the test winding (the lower winding) of idle-test relay 1012 in the event that the pre-final selector PS has been positioned, as described, by this time (as is usually the case) 50 and stop relay 1009 is, consequently, operated. If the stop relay is not operated, idle-test relay 1012 does not become connected up for the time being, but is connected up as soon as stop relay 1009 operates to signal that the pre-final selector 55 PS has been positioned on an idle final selector in the desired hundred-line group. When idle-test relay 1012 operates, its test circuit is from ground by way of the lower winding of the relay, contacts of the operated stop relay 1009, contacts 60 of relays 1101 and 1104 of the selector BPS, wiper 1117, conductor 1135, wiper 1225 of the selector BFS, individual conductor 1245, a jumper on the distributing frame DF10, individual test conductor 623 of the line of substation B, and thence to 65 battery through line-relay contacts and the cut-off relay of the line circuit of the called line, which line circuit may be like the line circuit LC, Fig. 1, of the line of substation A.

Upon operating, idle test relay 1012 at its inner 70 upper armature locks itself to the grounded conductor 933; at its middle lower armature it prepares to again ground the trunk test wiper 1029 under the control of final-test relay 1011; at its lower armature it opens the impulsing circuit 75 to prevent further movement of the wipers of

the by-pass final selector BFS in the event that the calling subscriber again manipulates his calling device; at its upper armature it disconnects the group-mark wiper 1114 and connects up the final-mark wiper 1115 of selector BFS; and at its 5 inner lower armature it applies ground potential by way of contacts of the final-test relay 1011 to the final-drive wiper 1028.

As a result of these circuit changes, marking potential from the lower terminal of the secondary winding of transformer 1013 is now extended through the operated upper armature of relay 1012 to the final-mark wiper 1115 of selector BPS, and thence by way of conductor 1137 and final-mark wiper 1220 of selector BFS, to the 10 final mark-conductor 1231. From conductor 1231, this marking potential extends to conductor 624 individual to the called line, by way of a jumper on the distributing frame DF10. Conductor 624 is thereby marked so that the final 15 selector FS will be stopped on the terminals of the called line (the line of substation B).

As a result of the ground potential extended to the final-drive wiper 1028 at the inner lower contacts of idle test relay 1012, a circuit is completed through conductor 438, for transfer relay 408, Fig. 4. Transfer relay 408 operates and at its upper armature further extends the ground potential through armature 441, negative wiper 501 of the switch TS, conductor 521, and contacts 30 of switching relay 610 of the final selector FS, to the driving magnet 609. Magnet 609 is therefore operated to drive the final selector in search of the marked conductor 624.

As a further result of its operation, transfer 35 relay 408 at its inner lower armature locks itself to conductor 333, now grounded through the line-mark wiper 1022 of the tie switch TS3, at the same time opening its initial operating circuit; it disconnects conductor 429, over which 40 the trunk test was previously made, from the trunk test wipers 405 and 510 of the pre-final selector PS, and extends it to the upper winding of line relay 402; it applies ground potential through the contacts controlled by armature 444 and through trunk-test wiper 505, to test conductor 525 to replace the ground potential previously applied thereto through trunk-test wiper 1029 by stop relay 1009; disconnects drive magnet 511 of the selector TS from conductor 440; it disconnects the idle-indicating potential previously applied by way of resistor 412 from link-test conductor 435, so as to maintain the selector PS guarded after the tie switch TS3 has restored; and at its inner upper armature it disconnects the group-test and final-test lead 437 from the group-test wipers 502 and 507 of the selector PS, and extends it by way of positive wiper 505, lead 523, and contacts of switching relay 610 to test wipers 604 and 608 of the final selector FS, so as to enable these wipers to operate with final-test relay 1011 to test for the marked called line.

The final selector finds the marked called line

When wiper 604 of the final selector FS reaches the marked conductor 624, a circuit is closed back over the positive conductor of the connection established between the final selector and the pre-final selector, and through the inner 70 upper armature of the operated transfer relay 408, contacts of switching relay 407, conductor 437, and wiper 1027 for relay 1011, now serving as the final test relay. When it energizes, test relay 1011 opens the driving circuit for mag- 75

net 609, thereby stopping final selector FS on the line of substation B, and it closes a prepared circuit for line relay 401 by way of contacts of the operated stop relay 1009, contacts of restored 5 delay relay 1010, contacts of the operated idle-test relay 1012, trunk test wiper 1029, and contacts of the operated transfer relay 408.

At this point it may be conveniently explained 10 that the function of delay relay 1010 is to prevent a premature establishment of the above traced circuit in the event that a by-pass selector such as BFS has already been positioned on an idle line (and the operation of the idle test relay 1012 is therefore awaiting only the energization 15 of stop relay 1009) before stop relay 1009 energizes responsive to an operation of the group and final test relay 1011 when the pre-final selector has found the level marked by the by-pass pre-final selector. Without the delay occasioned by the slow-releasing characteristic of relay 1010, idle test relay 1012 might immediately close the above traced circuit for line relay 202 and bring about a premature operation of the line relay of Fig. 4, without allowing time for 20 relay 1011 to restore and subsequently reoperate when the final test is completed.

Shift of control to the conversational train

At this time, the final selector FS has been positioned 30 on the terminals of the desired called line and the by-pass selectors (BPS, Fig. 11, and BFS, Fig. 12) may be restored, and the connection made through the tie switch TS3 may be broken. Pursuant to this, and also for the purpose 35 of transferring the control of the connection to the conversational train and of applying ringing current to the called line, line relay 402 energizes over the circuit above traced and closes a circuit for release relay 403. Release relay 403 grounds conductor 450, operating meter-control relay 405 through contacts of ring-cut-off relay 406; it makes an additional holding-potential connection to the incoming release trunk conductor 333 and its inner upper armature by 40 way of contacts of meter control relay 405 and contacts of ring cut-off relay 406; and it disconnects the incoming talking conductors 331 and 332 from conductors 434 and 433 extending to the bank of the tie switch TS3 and connects them instead to the windings of line relay 402, by way of contacts of back-bridge relay 404. Line 45 relay 402 is henceforth maintained energized over the calling line, independent of the above-traced initial energizing circuit through the tie switch TS3.

Switching through at the pre-final and final selectors

As a further result of the grounding of lead 50 450 by relay 403, switching relay 407 operates; at armature 444 and associated contacts it disconnects ground potential from trunk test wipers 505 and 510 and consequently from trunk test conductor 525 of the final selector FS, and applies ground potential to switching wipers 504 and 509 and consequently to switching conductor 524, extending to switching relay 610 of the final selector FS. As a result, switching relay 610 immediately operates and at its lower armature disconnects resistor 612 from the incoming trunk-test conductor 525 so as to maintain the final selector guarded; at its inner lower armature it disconnects the incoming positive conductor 523 from test wipers 604 and 608; at its inner upper armature it applies ground potential

through wiper 603 to the test conductor 623 of the called line so as to maintain the called line guarded and to maintain the cut-off relay thereof (not shown) in an energized condition; and it connects the incoming negative and positive line conductors 524 and 523 through the wipers 601 and 602 to the talking conductors 621 and 622 of the called line, at the same time disconnecting the incoming negative lead from drive magnet 609.

Applying ringing current to the called line

In the relay equipment of Fig. 4, switching relay 407 at armatures 443 and 441 completes the ringing circuit to the called line, at the same time disconnecting leads 437 and 438. The ringing current is obtained over the lead 410, and is ordinarily interrupted ringing current on which the negative potential of the exchange battery is superimposed. The ringing current passes out 15 through the upper winding of and through contacts of ring-cut-off relay 406 to the called line over the negative talking lead, and returns to ground over the positive talking lead, through contacts of the ring-cut-off relay 406. The 20 called subscriber is therefore signalled by ringing current in the usual manner. A small amount of ringing current passes through armature 442 and limiting condensers 413 to the called line to serve as an audible signalling indication.

Clearing out the by-pass pre-final selector BPS and the by-pass final selector BFS

Upon the previously described operation of release relay 403 and the consequent disconnection 35 of conductors 433 and 434 from the incoming line conductors 331 and 332, no further circuit exists for maintaining line relay 1102 of the by-pass selector BPS operated. Relay 1102 therefore restores, incidentally operating series relay 1104 momentarily, at the same time opening the circuit of release relay 1103. After a slight interval, release relay 1103 restores and opens the circuit of switching relay 1105 at its inner upper armature, permitting relay 1105 to restore and disconnect the associated wipers. At 40 its inner lower armature, release relay 1103 removes ground potential from start conductor 1119, thereby permitting relays 1007 and 1009 to restore. Idle-test relay 1012 is permitted to restore when ground potential is removed from conductor 933 at the middle upper armature of release relay 1103.

Release magnet 1113 is operated through off-normal contacts 1106 and through contacts of relays 1102 and 1103 to restore the selector BPS to its normal condition, whereupon the release-magnet circuit is opened at off-normal contacts 1106.

The tie switch TS3 and the by-pass selector BPS are now cleared out.

In the by-pass final selector BFS, release relay 1021 restores when test wiper 1116 is disconnected at the contacts of release relay 1103. Release magnet 1208 thereupon operates through off-normal contacts 1204 to restore BFS to its normal position, whereupon the release magnet circuit is opened at the off-normal contacts.

The by-pass train has been completely cleared out, and the connection set up through the conversational train is in ringing condition, signalling current being applied intermittently to the called line.

The called subscriber answers

When the called subscriber responds to the

signalling operation by removing his receiver (not shown) the usual direct-current circuit is closed over the conductors of his line for the upper winding of ring-cut-off relay 406 (which relay, as is well understood, does not respond to a flow of alternating current through its upper winding) operates sufficiently to close a locking circuit for itself at its lightly adjusted lower armature. Upon operating fully under the control of its lower winding, ring-cut-off relay 406 at its middle upper armature removes the return ground connection from the positive conductor and connects the positive conductor to the lower winding of back-bridge relay 404, while at its upper armature it disconnects the negative conductor from the ringing circuit and extends it to the upper winding of back-bridge relay 404. The two lines are now telephonically interconnected through the condensers which separate the line-relay bridge from the back bridge. Back-bridge relay 404 now energizes over the called line and reverses the connections between line relay 402 and the conductors of the calling line, thereby bringing about the reversal of current flow in the calling line, which may be used for supervisory or similar purposes if the call is from an operator's switchboard.

Metering the call

When the ring-cut-off relay 406 operates as above described, it disconnects the meter-control relay 405 from conductor 450 at the normally closed contacts controlled by its inner lower armature, so as to cause the slow-acting meter control relay 405 to restore after a slight interval. At the same time it connects the ungrounded positive pole of a so-called "booster" battery through the resistor 409, through the upper armature of the operated meter-control relay 405, and through contacts of release relay 403, to the incoming release-trunk conductor 333. This connection so increases the current flow through the marginally adjusted metering device 106 at the line circuit LC, that the call is registered, in the usual manner.

A moment later, meter-control relay 405 restores and reapplies ground potential to the incoming conductor 333.

It is to be noted that each test circuit in the by-pass train which includes a conductor at any of the conversational stages corresponding to conductor 343, Fig. 4, each includes an electro-polarized relay such as 109-711, Fig. 7, with the result that a test made while the booster-battery connection is in effect for the purpose of operating a meter such as 106 does not result in a false seizure, because of the fact that current flow through the test relay is reversed with respect to the current flow that obtains when a circuit is idle.

Clearing out the established connection when the called subscriber replaces his receiver first

Assuming that the called subscriber is the first to replace his receiver after the conversation has been terminated, back-bridge relay 404 restores and again reverses the current flow in the calling line to normal direction, while at its lower armature it removes ground potential at one point from locking conductor 450. Conductor 450 is, however, maintained grounded at the lower contacts of release relay 403. The circuits remain in this condition until the calling subscriber replaces his receiver, whereupon line relay 402, restoring, opens the circuit of release relay 403. Release relay 403 restores after a slight interval. Upon

restoring, relay 403 removes ground potential from conductor 333 at its inner upper armature, while at its lower armature, it removes ground potential from conductor 450. Relays 406, 407, and 408 now restore.

Switching relay 610 of final selector FS restores when relay 407, at armature 444, removes energizing potential from wiper 504 and conductor 524.

Cut-off relay 105 and switching relays 119 and 208 restore when relay 403 removes the energizing ground potential from conductor 333. Switching relay 119 reapplies idle-indicating potential by way of resistor 118 to conductor 136 to render the finder PF selectable to tie switches such as TS1; switching relay 208 reapplies idle-indicating potential through resistor 210 to conductor 236 to render the secondary finder SF selectable again to tie switches such as TS2.

The entire connection has now been released, and the switching equipment previously involved therein has been returned to common use.

Clearing out the connection when the calling subscriber replaces his receiver first

When the calling subscriber is the first to replace his receiver, back-bridge relay 404 remaining operated, holds ground potential on conductor 450. As a result, when release relay 403 restores it only brings about the clearing out of the preceding portion of the connection but does not restore relays 406, 407, and 408 to clear out the connection between Fig. 4 and the called line. The connection is maintained built up, therefore, from the relay equipment of Fig. 4 through the selectors PS and FS to the line of substation B, Fig. 6, as long as the receiver is off at the called substation, as the direct-current bridge across the line of substation B would operate the associated line circuit as though a call were being originated, if the called line were freed before the receiver is replaced.

When the receiver is replaced at the called substation, back-bridge relay 404 restores, finally removing ground potential at the last point from conductor 450 and permitting relays 406, 407, and 408 to restore. Switching relay 610, together with the cut-off relay (not shown) associated with the called line, restores responsive to the removal of ground potential from wiper 504 and conductor 524 at armature 444 of switching relay 407.

Operation when the called line is busy

Returning now to the point in the operation previously described at which the by-pass final selector BFS is being operated in a rotary motion to drive the wipers 1220 to 1225 across contacts sets 11 and 12 and into engagement with contact set 13, it will be recalled that series relay 1104 in selector BPS is held energized during the rotary movement of the final selector BFS, and that relay 1104, while operated, maintains the line-test wiper 1117 connected to busy relay 1101, and disconnected from idle-test relay 1102. Now, if the called line is busy, there is a ground potential on test conductor 623 thereof, rendering effective a circuit over conductor 1245, wiper 1225, conductor 1135, wiper 1117, and the upper armature of relay 1104, for busy-test relay 1101. Busy test relay 1101 is therefore in energized condition when the wipers of the switch BFS come to rest on bank contact set 13 and series relay 1104 restores. Under this condition, the restoration of series relay 1104 com-

5 completes a locking circuit for busy relay 1101 from line test wiper 1117 through the inner upper armature of relay 1101 and through the normally closed contacts controlled by the upper armature of relay 1104. With busy relay 1101 locked in operated position, the lower winding of idle test relay 1012 is maintained disconnected, at the middle upper armature of relay 1101, from test wiper 1117, and the ground potential encountered by line test wiper 1117 is extended by way of the upper contacts of the operated busy relay 1101, through busy wiper 1026 and conductor 436 to the upper winding of line relay 402, by way of busy relay 401. Busy relay 401 energizes in series with line relay 402 and prepares a locking circuit for its lower winding at its lower armature, at the same time disconnecting relays 407 and 408 from conductor 450. When line relay 402 operates and brings about the operation of release relay 403, ground potential is placed on conductor 450 to close a locking circuit for the lower winding of busy relay 401 to maintain relay 401 operated until the calling subscriber replaces his receiver.

25 At the upper contacts of busy relay 401, a connection is made from the associated common busy-tone lead to talking conductor 331, thereby causing busy signalling current to be transmitted back over the calling line to the called 30 subscriber.

35 Responsive to the energization of release relay 403 and the consequent disconnection of conductors 331 and 332 from conductors 434 and 433, line relay 1102 of the selector BPS restores and brings about the clearing out of the selectors BPS and BFS, together with the switch TS3, in the manner explained hereinbefore. A final selector, such as FS, has ordinarily been seized by this time, but is restored to common use when the ground potential previously applied to conductor 525 by way of trunk-test wipers 505 and 1029 is removed upon the deenergization of stop relay 1009 associated with the tie switch TS3.

45 When the calling subscriber replaces his receiver, line relay 402 restores and brings about the restoration of release relay 403, whereupon relay 401, being unlocked restores, as does meter control relay 405. The connection built up from the calling line through the finders PF and SF and the thousands selector TS to the pre-final selector PS is thereupon broken as hereinbefore described.

Overflow conditions

55 The way in which all-trunks-busy, or overflow, conditions are handled at the various switching stages will now be described. It is considered unlikely that an all-trunks-busy condition will often exist for any considerable length of time at the primary finders or at the secondary finders, for which reason no special provision has been made for taking care of such condition. Provisions such as ordinarily used in automatic systems wherein the conversational connections are set up through two-motion switches are 60 made at the by-pass thousands selectors to become operative when a by-pass thousands selector, such as BTS, Fig. 9, is unable to find an idle trunk line extending to a by-pass hundreds selector. Moreover, special provisions have been 65 made for taking care of the situation which arises when no idle trunk line in the desired group can be found accessible to a thousands conversational selector, such as TS, and provisions similar to those in the by-pass thousands selector BTS have been provided in the by-pass 70 75

pre-final selectors, such as BPF, which become operative in the event that the by-pass pre-final selector cannot find an idle by-pass final selector in the desired 500-line group.

Overflow condition at a by-pass thousands selector 5

Assume now that the by-pass thousands selector BTS has been taken for use as hereinbefore described, and that it has been operated responsive to a digit and caused to rotate over its bank contacts in a desired level in search of an idle trunk, but no trunk line is available for the moment in the desired level. In this event, the rotation continues until the wipers 921-925 have 10 been driven completely over the contacts in the selector level and the usual overflow contacts 908 and 909 have been actuated. Overflow contacts 909 disconnect the dial-tone transformer 951 and substitute the busy-tone transformer 952, to give a busy signal to the calling substation, while overflow contacts 908 close a reoperating circuit for series relay 903 to bring about an opening of the circuit of rotary magnet 911 and to again connect up the now-shifted overflow contacts 909 to the lower winding of line relay 901 so as to permit the busy-signalling current above mentioned to be transmitted back to the calling line.

When the calling subscriber replaces his receiver under this condition, the deenergization of line relay 901 is followed by the successive restoration of release relay 902 and series relay 903. Upon the restoration of release relay 902, the release magnet 912 is operated to restore the switch 30 to its normal position, whereupon the release magnet circuit is opened at off normal contacts 905. The overflow contacts 908 and 909 are shifted back to the position indicated in the drawings as soon as the releasing operation starts, 40 and the idle-indicating potential is reapplied through the off-normal contacts 907 to conductor 853 when the switch reaches its normal position. The clear-out of the relays associated with the tie switch TS2 occurs responsive to the removal of 45 ground potential from start conductor 855 by relay 902, and the clear-out of the distributor DS (in case it has not already occurred as hereinbefore described) occurs responsive to the removal of ground potential from the incoming 50 releasing trunk conductor 743 at contacts of release relay 902.

Overflow condition at the tie switch TS3

In order to explain the provisions for handling 55 an overflow condition which exists when there are no idle trunk lines over which a thousands selector such as TS can extend a connection into the thousands-line group indicated by the positioning of the by-pass thousands selector, such 60 as BTS, Fig. 9, it will now be assumed that the selector BPS, Fig. 11, and the tie switch TS3, Fig. 10, have been seized by the by-pass thousands selector BTS and that the second-stage tie switch TS3 is unable to find an idle trunk line accessible 65 to the thousands selector TS.

It will be recalled that group-test relay 1005 of the tie switch TS3 operated over the group test wiper 1021 and group-common conductor 300, of the thousands selector group in use and 70 from the secondary winding of transformer 811.

When the wipers of the tie switch TS3 arrive on the first trunk line accessible thereto of the group extending to the pre-final switches in the first thousands group from the selector group 75

containing the thousands selector TS, relay 1005 operates. Relay 1005 remains operated over conductors such as 431 and 334 of the successive trunks of the group as long as the wipers of the tie switch TS3 are advancing over trunks of the group in question. Since, according to the assumption made, all of these trunks are busy, link test relay 1002 does not operate to terminate the trunk hunting movement of the switch TS3 and bring about the operation of switching relay 1007. In this event, the two-step overflow relay 1004 is permitted to operate through its second step, its operation being as follows:

When group-test relay 1005 operates responsive to the arrival of group-test wiper 1021 on the first trunk line assigned to the group for which the search is being made, it closes a circuit through the relatively inefficient lower winding of two-step relay 1004, whereupon relay 1004 is energized sufficiently to close its lightly adjusted first-step contacts, the ones immediately above the relay, but not sufficient to operate its two lower armatures. Upon the closure of the upper locking contacts of relay 1004, a circuit for the two windings of the relay in series is closed, through contacts of switching relay 1007, to the grounded start conductor 1109. This locking circuit does not become effective as long as the initial circuit of the relay remains closed, but, as soon as group-test relay 1005 restores after the group being tested has been passed, the two windings of relay 1004 are energized in series, whereupon the relay operates fully. Ordinarily, the complete operation of relay 1004 does not take place as the locking circuit of the relay is opened at the contacts of switching relay 1007 before group test relay 1005 is permitted to restore.

Upon operating fully, two-step relay 1104 brings about the energization of transfer relays 1006 and 810 at its lower contacts, while at its inner lower armature it disconnects the incoming group-test and line-mark conductor 934 from the lower armature of transfer relay 1006 and extends it to the overflow-common conductor 1305, which conductor is common to all second-stage tie switches such as TS3 and is also common to all first-stage overflow circuits such as the one shown in Fig. 13. The operation of transfer relay 1006 is of no particular utility at this time, but transfer relay 810 of the tie switch TS2 disconnects group-mark wiper 829 and extends a connection through line-test relay 809 to the line-test wiper 828, at the same time extending ground potential through drive wiper 830 and conductor 240 to the driving magnet 307 of the thousands selector TS. The wipers 301-306 of the thousands selector TS now rotate until test wiper 303 or test wiper 306 encounters a marking potential, which will not occur until an overflow circuit such as Fig. 13 is reached, at which time the marking potential placed on overflow-common conductor 1305 is encountered by a test wiper 306 and permits line-test relay 809 to operate and terminate the movement of the wipers of the thousands selector by opening the circuit of driving magnet 307. At this time, line test relay 809 operates the clear-out relay 808 as before described, and clear-out relay 808 closes an operating circuit for switching relay 208, whereupon the calling line is extended through the wipers 304 and 305 to the line relay 1301 of the overflow circuit of Fig. 13. The tie switch TS2, the by-pass thousands selector BPS, and the by-pass pre-final selector BPS, together with

the tie switch TS3, clear out in substantially the same manner described hereinbefore.

In the overflow circuit, Fig. 13, the line relay 1301 operates release relay 1302 to disconnect the incoming test conductor from overflow-common conductor 1305 and to connect it to ground so as to form a holding circuit for the established connection. At its inner armature, release relay 1302 connects the busy tone lead 1304 through limiting condenser 1303 to the positive talking conductor to give a busy signal to the calling line.

The connection established to the overflow circuit of Fig. 13 is cleared out when the calling subscriber replaces his receiver and permits line and release relays 1301 and 1302 to restore.

It may be pointed out that two or three adjacent outlets in the bank of the thousands selectors such as TS may be provided for overflow circuits such as shown in Fig. 13, which overflow circuits may be common to all of the thousands selectors in the entire exchange.

It will be appreciated that this provision immediately frees the more expensive by-pass selectors and permits the busy condition to be handled from the conversational train.

Overflow condition at the pre-final by-pass selector BPS

An overflow condition at a by-pass pre-final selector, such as BPS, is handled in exactly the same way as explained in connection with the by-pass thousands selector BPS, that is, overflow contacts 1109 and 1110 are shifted when the wipers 1114-1118 have rotated beyond the last contact in a selected level. Contacts 1110 reoperate series relay 1104 from the inner upper contacts of release relay 1103 to open the circuit of rotary magnet 1112, so as to prevent further useless operation of the rotary magnet, and overflow contacts 1109 switch the lower terminal of the line relay from ground potential directly to ground potential by way of the secondary winding of a common busy tone transformer.

When the calling subscriber replaces his receiver after hearing a busy tone from the selector BPS, the deenergization of line relay 1102 causes the circuits involved to become cleared out as hereinbefore described.

Having described the invention, what is considered to be new and is desired to be protected by Letters Patent will be set forth in the following claims:

What is claimed is:

1. In a switching system wherein automatic hunting switching apparatus is used to make connection with an idle line in a predetermined group, two test circuits for joint use in testing a line, one circuit containing an individual ungrounded current source, the other including the grounded exchange battery, and means controlled jointly over said test circuits for positioning automatic switching apparatus on an idle line in a predetermined group.

2. In a switching system, groups of first lines, a separate group-common conductor assigned to each of said groups of lines, a separate group of second lines associated with each group of first lines, means for extending a connection to any one of said first lines, a hunting switch associated with the said connection and having access to all said second lines, means for operating said hunting switch in search of an idle second line, and means controlled over the group-common conductor associated with the connected first line for permitting said hunting switch to make con-

nection with an idle second line only in the event that it belongs to the group associated with that first-line group containing the connected line.

3. In combination, lines, finders for finding said lines when they are calling, said lines being divided into groups with a separate group of finders assigned to each group of lines, a separate start relay assigned to each group of lines, a distributor common to all of said lines and having access to all of said finders, means effective responsive to a calling condition of a line in any one of said groups and controlled jointly by the start relay assigned to such group and said distributor for causing said distributor to select a finder in the corresponding group, and means for causing the selected finder to find the calling line.

4. In combination, lines divided into groups, a separate group of finders assigned to a group of lines, a distributor common to all of said lines and having access to all of said finders, means for causing said distributor to come into communication with the finders successively when any one of the lines is in calling condition, said distributor including a group-test relay operable to indicate when the distributor is in communication with a finder in a group containing a calling line, a link-test relay in the distributor operable to indicate when the finder with which the distributor is in communication is idle, and means controlled jointly by said group-test relay and said link-test relay for bringing said distributor to rest in communication with an idle finder having access to the group of lines containing a calling line.

5. In combination, start relays each controlled from a separate group of lines, a hunting switch having a group-test relay and a link-test relay, links associated with said hunting switch divided into separate groups corresponding respectively to the groups of calling lines, means for starting said hunting switch in search of an idle link, means for controlling said group-test relay during the hunting operation in accordance with the respective positions assumed by the said start relays, and means controlled by the group-test relay for permitting said hunting switch to select an idle link only when such link is associated with a group of lines containing a calling line.

6. In combination, groups of primary finders, each group having access to a separate group of lines, groups of secondary finders, each group of secondary finders having access to a different plurality of primary finders, a primary tie switch having access to more than one group of primary finders, secondary tie switches each having access to more than one group of secondary finders, group-testing means and link-testing means associated with the primary tie switch and operable responsive to a calling condition of a line of one of said groups to select an idle primary finder in the corresponding group and for starting it in search of the calling line, means associated with the primary tie switch for marking the group of secondary finders having access to the selected primary finder, means also associated with the primary tie switch for selecting an idle secondary tie switch, and means associated with the selected secondary tie switch for selecting an idle secondary finder in the marked group and for starting the secondary finder in search of the selected primary finder.

7. In a switching system for interconnecting calling lines with called lines, serially related by-

pass selectors comprising a plurality of switching stages, the by-pass selectors at one switching stage having access to a number of separately designated groups of by-pass switches at the next switching stage, means for operating a train of said by-pass switches to set up a connection from a calling line to a called line, serially related main switches grouped in a manner corresponding to the grouping of the by-pass switches, tie switches interposed between the by-pass switches and the main switches at each switching stage, and means controlled through said tie switches for interconnecting a train of main switches to take over a connection temporarily established through the by-pass switches.

8. In a switching system, a switching stage including a group of by-pass switches and a group of take-over switches, means for seizing any idle one of said by-pass switches and for associating therewith any one of a number of idle take-over switches, by-pass links accessible to the seized by-pass switch and divided into separately designated groups, take-over links accessible to said take-over switches and correspondingly divided into groups, means for directing the by-pass switch into association with a desired group of by-pass links and for further directing it into connection with an idle by-pass link in the selected group, means associated with the by-pass link taken for use for marking a take-over link in the corresponding group, and means for operating the said associated take-over switch to effect a take-over connection to the marked take-over link.

9. In a switching system, a switching stage including a group of by-pass switches and a group of take-over switches, means for seizing any idle one of said by-pass switches and for associating therewith any one of a number of idle take-over switches, by-pass links accessible to the seized by-pass switch and divided into separately designated groups, take-over links accessible to said take-over switches and correspondingly divided into groups, means for directing the by-pass switch into association with a desired group of by-pass links and for further directing it into connection with an idle by-pass link in the selected group, means associated with the by-pass link taken for use for marking a take-over link in the corresponding group, means for operating the said associated take-over switch to effect a take-over connection to the marked take-over link, and means for releasing the connection set up through the by-pass switch, while leaving the connection through the take-over switch and the said marked take-over link intact.

10. In a switching system, a switching stage including a relatively small number of by-pass selectors and a relatively large number of take-over selectors, means for taking a by-pass selector for use and for thereupon associating an idle take-over selector therewith, groups of by-pass links accessible to said by-pass selector, correspondingly grouped take-over links accessible to said take-over selectors, means for operating said by-pass selector into association with a desired group of by-pass links and for further operating it to select an idle link in the group, means associated with the selected link for selecting and marking an idle take-over link in the corresponding take-over group, and means controlled through the connection set up by the by-pass selector for operating the take-over switch to hunt for and connect with the marked take-over link.

11. In combination, a switching stage comprising a group of main switches and an auxiliary switch common to the main switches, means for taking the auxiliary switch for use and for effecting a connection between the auxiliary switch and any one of the main switches in the group, separately designated groups of links accessible from the main switches, means for operating the auxiliary switch in accordance with the designation of any of said groups, said auxiliary switch being effective to mark the designated group, and means for causing the main switch associated with the auxiliary switch to hunt for the marked group and to select an idle link therein.

12. In a switching system, a group of lines, a by-pass link and a group of main links common to said group of lines, means controlled from any one of said lines in calling condition for setting up a connection from the calling line to said by-pass link, means responsive to the setting up of such connection for connecting the by-pass link with an idle one of the main links, means responsive thereto for setting up a main connection between the main link and the calling line, and means for subsequently clearing out the initial connection set up between the calling line and the by-pass link, as well as the connection between the by-pass link and the selected main link, while leaving the connection intact between the calling line and the main link.

13. In combination, lines divided into groups, a separate group of main switches having access to each of the groups of lines, an auxiliary switch having access to all of said lines, means for extending a connection to said auxiliary switch and for operating said auxiliary switch to make connection with any desired one of said lines, means controlled through the connection made by the auxiliary switch to the desired line for controlling the positioning of a main switch in the group to which the desired line belongs to position the main switch on the line, and means effective thereafter for transferring the connection to the line by way of the actuated main switch and for releasing and freeing the auxiliary switch for further operation while the connection made to the desired line is maintained through the actuated main switch.

14. In combination, two serially related switching stages including a main switch at the first stage, separately designated main switches at the second stage accessible to the said main switch at the first stage, a different group of lines accessible to each of the separate main switches at the second stage, said switching stages including also an auxiliary switch at the first stage and an auxiliary switch at the second stage accessible to the auxiliary switch at the first stage and having designations corresponding respectively to the designations of the said main switches at the second stage, the said second-stage auxiliary switch also having access to all the lines accessible to all of said main switches, means for taking the main switch at the first stage for use and for taking the auxiliary switch at such stage for use, means for operating the auxiliary switch at the first stage in accordance with any one of the designations assigned to the said auxiliary switch at the second stage, the first stage auxiliary switch responding in each case to extend connection to the second stage auxiliary switch, means for operating the second stage auxiliary switch to make connection with any line corresponding to the designation used in making connection to the second stage auxiliary switch, and means controlled through the connections set up by way of the

auxiliary switches for causing the first-stage main switch to select the one of the second-stage main switches which corresponds to the designation used in operating the first stage auxiliary switch, and for causing the selected second stage main switch to select the line accessible thereto which has been selected by the second-stage auxiliary switch.

15. In a switching system, a group of lines of a given numerical order, a plurality of separately designated groups of lines of a succeeding numerical order, a separate main switch assigned to each of the lines of the first numerical order, each main switch having access to all of the lines of said succeeding numerical order, an auxiliary switch common to all of the said lines of the first numerical order, means for taking any one of the said lines of the first numerical order into use and for rendering the said auxiliary switch temporarily individual to such line, means for operating the auxiliary switch in accordance with the designation of any desired one of the groups of lines of the said succeeding numerical order, and means responsive thereto for causing the main switch assigned to the line in use to associate itself with the group bearing the designation in accordance with which the auxiliary switch has been operated and to select and seize an idle line in the said group.

16. In combination, a group of lines of a first numerical order, separately designated groups of lines of a succeeding numerical order, a first marking switch common to the lines of the said first numerical order, separately designated groups of marking switches accessible to said first marking switch, means for rendering said first marking switch temporarily individual to any line of the first numerical order, means for setting the first marking switch in accordance with a desired designation to select an idle succeeding marking switch in a desired group and to mark the corresponding one of the said groups of lines of succeeding numerical order, and means controlled through the marking thus effected for interconnecting an idle line in the marked group with the line of the first numerical order to which the first marking switch has been rendered temporarily individual.

17. In combination, a group of lines of a first numerical order, separately designated groups of lines of a succeeding numerical order, control mechanism common to the said lines of the first numerical order, means for rendering said control mechanism temporarily individual to one of said lines of the first numerical order, means for operating the control mechanism in accordance with the designation assigned to a desired one of the groups of lines of the second numerical order, means controlled through the operated control mechanism for selecting and marking an idle line in the desired group, and switching mechanism associated with the line of the first numerical order to which the control switch has been rendered temporarily individual for bringing such line into connection with the marked line of the said succeeding numerical order.

18. In a by-pass switching system, a switching stage including a first group of lines accessible in common to a first group of switches, a second group of lines accessible in common to a second group of switches, a group-common conductor assigned to the first group of lines and associated switches, a second group common conductor assigned to the second group of lines and associated switches, means for closing variable by-pass con-

nnections around said switching stage by interconnecting a line of either of said groups with any one of the switches having access to such line, and testing means controlled over the associated group common conductor in each case for directing the setting up of the by-pass connection.

19. In a by-pass switching system, a switching stage including a first group of lines accessible in common to a first group of switches, a second group of lines accessible in common to a second group of switches, a group-common conductor assigned to the first group of lines and associated switches, a second group common conductor assigned to the second group of lines and associated switches, means for closing variable by-pass connections around said switching stage by interconnecting a line of either of said groups with any one of the switches having access to such line, testing means controlled over the associated group common conductor in each case for directing the setting up of the by-pass connection, and means effective after the by-pass connection has been set up for operating the by-passed switch to establish a take-over connection from the concerned line through the switch and for subsequently severing the by-pass connection, while leaving the take-over connection intact.

20. In a switching system, a group of switches having access to separately designated groups of trunks, another group of switches of the same numerical order having access to similarly designated groups of trunks, a group-common conductor common to the switches and associated trunks of the first group, a second group-common conductor associated with the switches and associated trunks of the second group, means for taking any one of said switches in either group for use and for thereupon placing a distinctive marking on the associated group-common conductor, means responsive to a designation of a desired group of trunks for preparing a by-pass connection around the switch taken for use to the designated group, means for subsequently testing the said group common conductors and for testing the trunks in both groups bearing the said desired designation, and means controlled jointly in accordance

with the marked condition of said group-common conductor and by the busy or idle condition of the trunks bearing the desired designation for selecting an idle trunk in the designated trunk group accessible to the switch which has been taken for use.

21. In a switching system, a group of switches having access to separately designated groups of trunks, another group of switches of the same numerical order having access to similarly designated groups of trunks, a group-common conductor common to the switches and associated trunks of the first group, a second group-common conductor associated with the switches and associated trunks of the second group, means for taking any one of said switches in either group for use and for thereupon placing a distinctive marking on the associated group-common conductor, means responsive to a designation of a desired group of trunks for preparing a by-pass connection around the switch taken for use to the designated group, means for subsequently testing the said group common conductors and for testing the trunks in both groups bearing the said desired designation, means controlled jointly in accordance with the marked condition of the said group-common conductor and the busy or idle condition of the trunks bearing the designed designation for selecting an idle trunk in the designated trunk group accessible to the switch which has been taken for use, means for marking the trunk line to which the by-pass connection has been extended, and means for operating the switch taken for use to test for and locate the marked trunk to effect a main connection with the trunk independent of the by-pass connection.

22. In a switching system wherein the setting up of the main connection through successive links is controlled by the setting up of preliminary by-pass connections through by-pass stages corresponding respectively to the main switching stages, a control circuit located in a by-pass link at a given by-pass switching stage, and means in said control circuit for controlling the positioning of main switches in two switching stages.

JOHN WICKS.
